[57] CLAIM

The ornamental design for a malfunction display panel for xerographic copying machine, substantially as shown and described.

DESCRIPTION

FIG. 1 is a front elevational view of a malfunction display panel for xerographic copying machine, showing our new design;

FIG. 2 is a rear elevation view thereof;

FIG. 3 is a top plan view thereof, the bottom plan view being a mirror image of said top plan view; and

FIG. 4 is a left side elevation thereof, the right side elevation view being a mirror image of said left side view.

The lines shown on the front surface in FIG. 1 indicate transparent areas on an otherwise opaque surface. The black circles indicate transparent areas within which opaque letters and numerals are located.
